UNITED STATES PATENT OFFICE.

BENJAMIN LA FAYETTE HENDRICKS, OF MACON, GEORGIA.

AUTO SAFETY LOCKING DEVICE.

1,331,642.

Specification of Letters Patent. Patented Feb. 24, 1920.

Application filed September 16, 1919. Serial No. 324,245.

To all whom it may concern:

Be it known that I, BENJAMIN L. HENDRICKS, a citizen of the United States, residing at Macon, in the county of Bibb and State of Georgia, have invented certain new and useful Improvements in Auto Safety Locking Devices, of which the following is a specification, reference being had to the accompanying drawings.

10 This invention relates to certain improvements in locking devices, and it is primarily an object of the invention to provide a novel and improved device of this general character particularly adapted for use in connection with the operating members of a transmission of the type as employed in connection with the well known Ford automobile, and which device provides means whereby the use of the automobile by an unauthorized person is substantially prevented.

15 The invention consists in the details of construction and in the combination and arrangement of the several parts of my improved locking device whereby certain important advantages are attained and the device rendered simpler, less expensive and otherwise more convenient and advantageous for use, as will be hereinafter more fully set forth.

20 The novel features of my invention will hereinafter be definitely claimed.

25 In order that my invention may be the better understood, I will now proceed to describe the same with reference to the accompanying drawings, wherein:

30 Figure 1 is a view in plan of a locking device constructed in accordance with an embodiment of my invention and in applied position, the coacting levers being shown in section;

35 Fig. 2 is a view in side elevation of my improved locking device, as herein embodied, with the coacting levers in fragment and the supporting base in section, said figure being somewhat diagrammatic, and,

40 Fig. 3 is a view in end elevation of my improved device, as herein disclosed.

45 As disclosed in the accompanying drawings, 1 denotes a plate adapted to be anchored to the body of an automobile or the like and to one side of the operating levers, and which plate is provided with a staple or eye 2 to which is engaged an end portion of a hasp 3. The connection of the hasp 3

5 with the staple 2 is afforded by a slot 4 produced in an end portion of the hasp 3 which permits an endwise movement of the hasp 3 in order to move the same out of the way when not in use. The operating levers comprise a clutch lever, the reverse lever and the brake lever all moving or swinging substantially in the same direction.

60 The opposite end portion of the hasp 3 is provided with an open slot 5 which is adapted to receive the brake lever, and said lever is held within said slot through the instrumentality of a lock E in a manner which is particularly set forth in my co-pending application, executed of even date herewith. At a point substantially midway its length, the hasp 3 is provided in its side portion with a slot 6 extending longitudinally of the hasp 3 and having its end remote from the slot 4. This second open slot 6, when the device is applied in locking position, receives the lever of the clutch when the same is in neutral position. The opposite side of the hasp 3 slightly in advance of the slot 6 is provided with a lug 7 which contacts with the reverse lever, when the device is in locking position, to hold said reverse lever against movement.

65 From the foregoing description, it is thought to be obvious that a locking device constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

70 I claim:

75 1 A locking device adapted for use with a plurality of levers arranged side by side and moving in the same general direction consisting of a member supported independently of the levers and to one side thereof, a hasp having one end portion slidably and swingingly engaged with the member, the opposite end portion being provided with an open slot to receive the lever remote from the member, means for locking said lever within the slot, said hasp inwardly of the slot being provided with an-

other open slot to receive the lever next to the member, said hasp being provided with a lug to engage an intermediate lever to hold the same against movement when the hasp is in locking engagement with the levers received within the open slots.

2. A locking device adapted for use with a plurality of levers arranged side by side and moving in the same general direction, consisting of a member supported independently of the levers, and to one side thereof, a hasp having one end portion slidably and swingingly engaged with the member, the opposite end portion being provided with an open slot, to receive the lever remote from the member, means for locking said

lever within the slot, said hasp inwardly of the slot being provided within a longitudinal margin thereof with a second open slot facing in the same direction as the first-named slot, said second slot receiving the lever next to the member, the opposite side marginal portion of the hasp in advance of the second slot being provided with a lug to engage an intermediate lever to hold the same against movement when the hasp is in locking engagement with the levers received within the open slots. 20 25

In testimony whereof I hereunto affix my signature.

BENJAMIN LA FAYETTE HENDRICKS.
